EDWARD G. GERMER, OF ERIE, PENNSYLVANIA.

DESIGN FOR A HEATING-STOVE.

SPECIFICATION forming part of Design No. 28,386, dated March 15, 1898.

Application filed October 7, 1897. Serial No. 654,470. Term of patent 7 years.

To all whom it may concern:

Be it known that I, EDWARD G. GERMER, a citizen of the United States, residing at the city of Erie, in the county of Erie and State of Pennsylvania, have invented a certain new and original Design for Heating-Stoves; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

The drawing shows a perspective view of a heating-stove.

The leading features of my design consist substantially in the form and ornamentation of a heating-stove embodying a stove-base rectangular in its general contour, under which there is a skirting joining the legs at the corners of the base and ornamented with scrollwork, said stove-base being surmounted by an upright generally rectangular body comprising an ash-pit section having a door in front and ornamental brackets supporting side rails at the sides, surmounted with fire-pot and combustion-chamber sections provided with illuminated doors at the front and sides thereof, and a sub-top and top section ornamented with scrollwork panels.

A is the stove-base, which is substantially rectangular in its general outline, with the corners thereof rounded and having a plain ogee band A' around the lower edge thereof. The front of the base above this molding is occupied with a name-plate panel a, with an ornamental border around the same. At the corners of the base are corner-panels a' and at the sides side panels a'', the lower portions of which are ornamented with a band of shell-work, above which the corner and side panels a' and a'' are ornamented with scrollwork.

Under the corners of the base A are secured legs B, the upper parts of which form the corner-panels of the skirting C, the panels of the skirting C and on the legs B being ornamented with scrollwork c. The lower portions of the legs B are curved outward and ornamented with scroll and foliate work.

Upon the top of the base A there is the ash-box section D, comprising corner-posts

D', a door D² in the front thereof, having a sliding draft-register and ornamented with scrollwork, and scrollwork brackets d at the 55 sides of the ash-box supporting ornamental rails d'. Above the ash-box section D there is a projecting molding E, ornamented around its lower edge by plain and shellwork bands, above which, in front, is a name-plate panel 60 e and at the corners and sides a plain ogee. Above this molding is the section F, designated as the "fire-pot" section, comprising corner-posts F' and illuminated front doors f f, centrally curving outward, and illuminated doors f' at the sides thereof, the stiles of these doors being ornamented with scroll-work. This section F is surmounted with a projecting band molding G, the lower edge of which is a plain ogee and the upper part 70 a shellwork band. Above this molding G is the combustion-chamber section H, comprising corner-posts H' and illuminated front doors h h, centrally curving outward, and illuminated side doors h', the stiles thereof 75 being ornamented with scrollwork.

The sub-top section I of the stove surmounts the section H and comprises the corner-sections J, ornamented with scrollwork, the front panel K, the contour of the top of 80 which is substantially circular, and the front thereof shaped like a semidome and ornamented with medallions and scrollwork. Each of the side panels K' between the corner-sections J J consists of a scrollwork panel k, 85 above which there is a substantially semicircular panel k', ornamented with bas-relief work. Above these corner-sections J and the front and side panels K and K' there is a substantially vertical band L, ornamented 90 with scrollwork.

The top section M surmounts the ornamental band L and comprises a lower section M', which curves upward and inward to the base of the dome-shaped upper section N, 95 upon which is placed an urn O.

The lower section M' of the stove-top is divided into corner-panels m and front and side panels m', ornamented with scrollwork, the lower edges of these panels terminating 100 in a plain band m², which overhangs the sub-top section I and the ornamental band L. The upper section N of the stove-stop M comprises a shellwork band n around the base

thereof, above which there is a plain band n' , the upper edge of which is scroll-ornamented. Above the band n' is a curved band n^2 , ornamented with scrollwork, which is sur-
5 mounted by the base O' of an ornamental urn O , provided with scrollwork and medal-
lion ornamentation, and scrollwork handles
 $o o$ on the sides thereof.

What I claim is—

The design for a heating-stove, substan-
tially as shown and described.

In testimony whereof I affix my signature
in presence of two witnesses.

EDWARD G. GERMER.
